POWER-OPERATED PNEUMATIC TOOL

Alexander Palmros, Rochester, Pa.

Application November 13, 1936, Serial No. 110,676
Renewed February 1, 1939

18 Claims. (Cl. 125—34)

My invention relates, generally, to power-operated pneumatic tools of the percussion type, and, more particularly, to tools such as pavement cutters, rock drills, tampers, pile drivers, and the like, wherein a power source in the form of a motor or engine is utilized to actuate a working piston which produces and controls the fluid-pressure such, for example, as air pressure, to actuate a floating hammer member.

10 The object of my invention, generally stated, is to provide a fluid-pressure percussion tool which shall be of relatively simple and light-weight construction, economical and efficient in operation and which may be readily and economically manufactured.

15 A more specific object of my invention is to provide for utilizing a motor or engine for actuating the working piston in a fluid-pressure percussion tool through the agency of a crank-driven crosshead.

20 Another object of my invention is to provide for utilizing oppositely rotating cranks for imparting a reciprocatory motion to a crosshead for actuating a piston.

25 A further object of the invention is to provide for actuating the working piston in a fluid-pressure tool by means of oppositely driven rotatable gear members arranged to reciprocate a crosshead attached to the piston.

30 A still further object of my invention is to provide for actuating a reciprocatory crosshead member by means of a motor or engine in such manner that balanced driving forces are always applied to the crosshead member.

35 Another object of my invention is to provide a fluid-pressure operated tool in which the fluid-pressure is released from a pressure chamber by the action of the working piston.

40 Another object of my invention is to provide for controlling the fluid-pressure in a tool of this character by means of a valve which is actuated in accordance with the position of the working piston.

45 A further object of my invention is to provide a fluid-pressure actuated tool having a working piston and a floating hammer within a common cylinder wherein the piston is utilized to produce pressure and to actuate a valve to release the pressure to actuate the hammer.

50 These and other objects of my invention will become more apparent from a study of the following detailed description, in conjunction with the drawings, in which:

55 Figure 1 is a sectional view of a device embodying the principal features of the invention;

Fig. 2 is a sectional view of the transmission casing showing the crosshead;

Fig. 3 is a view of the tool chuck;

Fig. 4 is a plan view of the crosshead showing the opposed paths of movement of the cranks; 5 and

Fig. 5 is a partial sectional view of the device illustrated in Fig. 1 showing a modification thereof.

The principles of the invention will be described in connection with their application to a pavement cutter, although it is to be understood that the invention may be as readily utilized in tools of other kinds.

In practicing my invention in its preferred 15 form, the device comprises three main elements, namely, a cylinder element, a transmission element, and a power element, the transmission element being of such nature that it will transform the rotary motion of the power element into reciprocatory motion to actuate a piston in the cylinder element.

In this embodiment of the invention, all three 20 of these elements are combined to produce a unitary device or tool of compact and light-weight construction. In case the invention is applied to other types of machinery, it may be necessary or advisable to utilize a separate power element.

The cylinder element comprises generally a 25 cylinder member housing a working piston and a floating hammer. The cylinder member is provided at one end with a compression chamber, and at the other end with a tool chuck, which 30 closes this end of the cylinder.

The compression chamber is provided with a packing box through which extends the piston rod attached to the piston. The pressure chamber is further provided with an intake valve 40 through which air is drawn on each down stroke of the piston, and which automatically closes on each compression stroke.

The tool chuck end is provided with suitable 45 uncontrolled ports, and the cylinder is further provided with a port, at a point near the end of the piston travel and which is open when the hammer is in its fully down position in contact with the end of the tool in the chuck. The arrangement of these ports is such that on the up or compression stroke, the fluid or air between the adjacent faces of the piston the hammer is rarefied to such an extent as to cause the hammer to follow or trail the piston to a retracted 50 position where it may be acted upon by the com- 55

pressed air when released from the pressure chamber.

The compressed air in the pressure chamber is released to drive the hammer into engagement with the tool by means of a self-closing sleeve valve at the pressure chamber end of the cylinder, which controls a plurality of ports around the cylinder wall, which are uncovered by the piston at the end of its compression stroke. The sleeve valve is moved from its seat over the ports by the piston as it approaches the end of its back or compression stroke.

Upon the opening of the sleeve valve, the hammer is "shot" forward by the expansion of the compressed air. This movement of the hammer is followed by the piston, which causes fresh air to be drawn into the pressure chamber and cylinder through the intake port, while the used air is exhausted through the port in the cylinder which is uncovered by the hammer as it strikes the tool. Thus, a supply of fresh cool air is provided for each working cycle.

The transmission element comprises a casing suitably secured to the pressure chamber and which houses the mechanism for actuating the piston. The piston rod is secured to a cross-head mounted within the casing on suitable guides for sliding movement thereon. The cross-head is given a reciprocatory motion by means of two oppositely turning cranks suitably journaled in the sides of the casing which in this instance, are in the form of bevel gear wheels oppositely disposed and in driving engagement with a common pinion driven by the power element, so that the bevel gears rotate in opposite directions at the same speed.

The bevel gear wheels are provided with crank pins near their periphery, which engage sliding bearing blocks carried in slots on opposite sides of the crosshead in such manner that equal and balanced forces are imparted to the crosshead throughout its whole range of movement.

In this instance, the common pinion is keyed to the end of the motor shaft and the motor is suitably attached to the end of the transmission casing. The pinion may be driven by a separate power source, if desired.

Referring now to Fig. 1 of the drawings, 10 designates the cylinder element, 11 the transmission element, and 12 the motor or power element.

The cylinder element 10 comprises a cylinder member 13 which is provided at one end with a tool chuck 14 for holding a suitable tool 15, and at the other end, with a fitting 16 which forms a pressure chamber 17.

Within the cylinder there is provided a piston 18 and a floating hammer member 19 which functions, in a manner to be described herein-after, to subject the tool 15 to impact blows in order to accomplish the desired kind of work.

The piston 18 is attached to the working elements of the transmission element 11 by means of the piston rod 21, which extends through a suitable packing gland 22 formed in the fitting 16.

In this instance, the hammer member 19 is actuated by compressed air, which is produced in the pressure chamber 17 on each back or compression stroke of the piston 18 as it is reciprocated by the transmission element 11 and motor 12. The tool chuck 14, which closes one end of the cylinder, is provided with suitable open ports 23 and 24 and the cylinder is provided with a port 25, this arrangement being such that on the back stroke of the piston, the difference in air

pressure on the opposite faces of the hammer causes it to trail the piston to a retracted position where it may be subjected to a driving force by the compressed air in the pressure chamber.

The pressure chamber 17 is provided with a suitable air inlet valve 26 which functions on the down or expansion stroke of the piston to emit a fresh charge of air into the pressure chamber and cylinder through the ports 20 and which automatically closes on the compression stroke to seal the chamber.

In order to effect the release of the compressed air in the chamber 17 at the proper time to subject the hammer 19 to a driving force, the end of the cylinder which extends within the pressure chamber 17 is provided with a plurality of openings or ports 27, which are normally held closed by a sleeve valve 28 that is self-closing by means of a coil spring 29.

The valve 28 is so constructed that it is actuated to its open position to open the ports 27 by the piston 18 as it reaches or nears the end of its back stroke. In this instance, the valve 28 is provided with an integral collar portion 30, 25 which extends to a point within the path of movement of the piston so that it engages the back face of the piston as it approaches the end of its back stroke. From this point until the piston reaches the end of its back stroke, the valve is actuated toward its open position against the force of its biasing spring 29. The ports 27 are so positioned that they are uncovered by the piston 18 at or near the end of its back stroke, thus permitting the discharge of compressed air to enter the cylinder between the adjacent faces of the piston and the hammer. This subjects the hammer to a sudden force, thus forcing it downward into engagement with the end of the tool 15, as shown.

In view of the foregoing, it will be apparent that the used air is discharged through the port 25 and a fresh charge of cool air is drawn in through the inlet valve 26, which automatically opens on the down stroke of the piston. The expansion of the air in the cylinder provides a cooling effect upon the cylinder and working parts. The entrance of the fresh charge of air provides a further cooling effect and insures that there will always be a sufficient supply of air to properly actuate the hammer.

The piston 18 may be reciprocated in any suitable manner. However, in this embodiment of the invention, a power transmission element 11 is provided, which is adapted to drive the piston in a straight-line motion, and which is of light-weight and compact construction in order that it may be attached directly to the cylinder element. The preferred form of transmission element comprises a gear casing 31, which may be secured to a spacer sleeve 9 by suitable bolts 32. In order to give the piston 18 a straight-line motion, the piston rod 21 is connected to a crosshead 33, which is mounted within the casing 31 upon suitable guides 34 (see Fig. 2) in such manner that it may be reciprocated along the same line of movement as the piston.

In order to actuate the crosshead 33, the transmission element is provided with a pair of crank members 35 and 36, which in this instance, are 70 in the form of bevel gear wheels mounted within the casing on opposite sides of the crosshead in suitable bearings, as shown.

As shown best in Fig. 1, the crosshead 33 is provided with longitudinal slots 37 on opposite sides 75

thereof. The crank members 35 and 36 are connected to the crosshead by means of driving lugs 38, which engage bearing blocks 39 slidably mounted in the crosshead slots. These bearing blocks slide back and forth in opposite directions within the crosshead slots 37 as the cranks rotate, thus imparting a straight-line reciprocating movement to the crosshead and piston. The bearing blocks 39 may be in the form of rollers if desired.

It is apparent that the crosshead 33 may be actuated by the use of a single crank. However, in order that the crosshead will be subjected to balanced driving forces at all times and to reduce the wear upon the guides 34 to a minimum, provision is made for actuating the cranks in opposite directions at the same speed. As will be understood with reference to Fig. 4, the rotation of the cranks in opposite directions causes the crank pins to move in a path designated by the circle, the diameter of which determines the piston travel. The relative position of the crank pins 38 is the same at all times, thus subjecting the crosshead to equal and balanced driving forces throughout its complete stroke.

In this instance, the cranks 35 and 36 are actuated by means of a single pinion gear 40, which is attached directly to the shaft 41 of the motor 12. The motor frame 43 may be attached directly to the casing 31 by means of bolts 44, as shown.

Referring to Fig. 3, which is an enlarged view of the tool chuck 14, it will be observed that it is provided with a longitudinal bore 45 which receives the end of the tool 15. The tool 15 is slidably mounted within the bore and is provided with a collar 46, which engages the end of the chuck.

The tool chuck 14 may be secured to the cylinder 18 in any suitable manner, such for example, as by means of tie bolts 47 extending through the lugs 48 on opposite sides thereof, as shown in Fig. 3. The tie bolts may be anchored in any desired manner (not shown) to the spacer sleeve 10, which is interposed between the fitting 16 and gear casing 31. As will be readily understood, these tie bolts function to unite all of the parts between the spacer sleeve and tool chuck.

As shown in Fig. 5, the cylinder 13 may be provided with a plurality of exhaust ports 25 which are controlled by a spring loaded valve of any suitable type. As illustrated, the valve comprises a ring element 49 surrounding the cylinder which is biased to a closed position by springs 50 carried in suitable openings in the end of the tool chuck 14.

As will be readily understood, the valve ring 49 will be positively closed when the piston 18 reaches the end of its stroke and before the hammer 19 reverses its direction of movement.

The invention as disclosed provides an efficient light-weight and compact tool of the pneumatic type, which is electrically operated. The principles of this invention may be applied to tools of different form, which in some cases, may have a separate or independent driving element, in which case the transmission element 11 may be actuated from a common power source in the form of an engine by means of a flexible shaft or other suitable means.

It is apparent that a device of the kind described possesses many advantages over other forms of pneumatic percussion tools now in common use. In addition to its light weight and compact construction, it may be supplied with

power from any suitable source of electrical energy through an insulated cable and used with the same ease and flexibility as motor operated drills and the like are now used.

It is so constituted that it inherently functions to supply its own compressed air, thus entirely eliminating the use of air compressors and air hose.

The efficiency is relatively high as compared to the older types of pneumatic percussion tools, for the reason that the air is compressed and expanded within the same cylinder. The compression chamber receives a full charge of fresh air on each stroke of the piston and is tightly sealed by the valves and piston during the compression period. Thus, there are no leaks and no deficiency in the air supply. The drop in temperature of the air during the expansion thereof assists in cooling the cylinder and other parts.

It may be stated, in conclusion, that while the illustrated and described example constitutes a practical embodiment of my invention, I do not wish to limit myself strictly to the exact details herein illustrated, since modifications of the same may be made without departing from the spirit of the invention, as defined in the appended claims.

I claim as my invention:

1. In a fluid-pressure driven tool, in combination, a cylinder, a working piston therein, power means having a rotating element for driving the piston, a slidably mounted crosshead attached to the piston, a pair of rotatable cranks mounted on opposite sides of the crosshead on a common axis of rotation and in driving engagement with the crosshead, and gear means connecting the said cranks to the rotating element of the power means whereby the cranks are driven in opposite directions simultaneously.

2. In a fluid pressure driven tool, in combination, a cylinder, a working piston therein, a motor for driving the piston, a crosshead secured to the piston and mounted for reciprocatory movement therewith, a pair of gear wheel cranks disposed in driving engagement with the crosshead and rotatably mounted on a common axis on opposite sides thereof, and a gear driven by the motor and disposed in driving engagement with the gear cranks for driving said gear cranks in opposite directions simultaneously.

3. In a fluid pressure driven tool, in combination, a cylinder, a working piston therein, a motor for actuating the piston, a crosshead, a piston rod interposed between the crosshead and piston, guides for slidably supporting the crosshead for reciprocatory motion in line with the piston, a pair of crank members rotatably mounted on a common axis of rotation on opposite sides of the crosshead and disposed in driving engagement with the crosshead, gear teeth on each of said crank members forming gear wheels thereof, and a pinion gear mounted on the end of the motor shaft and engaging the gear teeth on each crank member whereby on rotation of the motor the crank members are simultaneously rotated in opposite directions to impart balanced driving forces to the crosshead.

4. In a fluid pressure driven tool, in combination, a cylinder, a working piston therein, a motor for driving the piston, a crosshead attached to the piston and mounted for reciprocatory movement therewith, said crosshead having longitudinal slots on opposite sides thereof, a bearing member slidably mounted in each slot, a pair

- of cranks rotatably mounted on a common axis on opposite sides of the crosshead and engaging the bearing members in the crosshead slots, and driving means connecting the cranks to the motor shaft operable to cause said cranks to be driven simultaneously in opposite directions in response to the rotation of the motor shaft thereby to reciprocate the crosshead by the application thereto of balanced driving forces.
5. In a fluid pressure-driven mechanism, in combination, a working piston, a motor for actuating the piston, a crosshead secured to the piston, and means comprising oppositely rotating gears provided with lugs engaging the crosshead and mounted on a common axis driven by the motor for imparting a reciprocatory motion to the crosshead and piston.
10. In a fluid pressure-driven mechanism, in combination, a cylinder, a working piston in the cylinder, a crosshead attached to the piston, said crosshead being mounted for reciprocatory movement and having an elongated recess on opposite sides thereof, a pair of gears mounted for rotation about a common axis and provided with driving lugs engaging said recesses, and means for rotating the gears in opposite directions at the same speed to reciprocate the crosshead and piston.
15. In a fluid pressure-driven mechanism, in combination, a cylinder, a working piston in the cylinder, a crosshead attached to the piston, said crosshead being mounted for reciprocatory movement and having an elongated recess on opposite sides thereof, a pair of gears mounted for rotation about a common axis on opposite sides of the crosshead and in planes parallel to the path of movement of the crosshead, said gears having driving lugs engaging the recesses in the crosshead, and means for simultaneously driving the gears in opposite directions.
20. In combination, a piston, a crosshead attached to the piston and mounted for reciprocatory movement in the same plane of movement as the piston, said crosshead having oppositely disposed longitudinal slots on opposite sides thereof, a pair of cranks mounted for rotation on a common axis engaging said slots in the crosshead and adapted when rotated in opposite directions to reciprocate the piston, and motor operated means for driving the cranks in opposite directions at the same speed.
25. In a power actuated pneumatic hammer, in combination, a cylinder having a piston therein, a power transmission casing attached to one end of the cylinder, a crosshead mounted in the casing for reciprocatory movement in line with the movement of the piston and having longitudinal slots on opposite sides thereof, means for attaching the piston to the crosshead, a pair of cranks mounted within the casing engaging said slots in the crosshead and disposed to rotate in opposite directions on a common axis to reciprocate the crosshead, and means including a motor attached to the casing opposite the cylinder for driving the cranks in opposite directions at the same speed.
30. In a fluid pressure-actuated tool, in combination, a cylinder, a piston and a floating hammer in the cylinder, means for reciprocating the piston, a pressure chamber at one end of the cylinder, and a spring biased valve controlled by the action of the piston for releasing the fluid-pressure from the pressure chamber into the cylinder between the adjacent faces of the piston and hammer to actuate the floating hammer.
35. In a fluid pressure-actuated tool, in combination, a cylinder provided at one end with a tool holding chuck and at the opposite end with a pressure chamber, a working piston and a floating hammer in the cylinder, means for reciprocating the piston, and mechanical valve means actuated in accordance with the piston position for releasing the fluid pressure of the pressure chamber into the cylinder in front of the hammer.
40. In a fluid pressure-actuated tool, in combination, a cylinder provided at one end with a tool holding chuck and at the opposite end with a pressure chamber, a working piston and a floating hammer in the cylinder, means for reciprocating the piston, a self-closing valve operable to release the fluid pressure of the pressure chamber into the cylinder, and means whereby the valve is actuated to the open position by the piston at the end of its compression stroke to release the said fluid pressure into the cylinder between the adjacent faces of the piston and hammer to subject the hammer to an actuating pressure.
45. In a fluid pressure-actuated tool, in combination, a cylinder provided at one end with a tool holding chuck and at the opposite end with a pressure chamber, a working piston and a floating hammer in the cylinder, means for reciprocating the piston, a self-closing intake valve in the pressure chamber, and a self-closing valve actuated by the piston at or near the end of its compression stroke for releasing the pressure into the cylinder to actuate the hammer from a retracted to an impact position.
50. In a power-driven pneumatic tool, in combination, a cylinder housing a working piston and a floating hammer, means for reciprocating the piston, a pressure chamber at one end of the cylinder, a self-closing intake valve in the pressure chamber, and a self-closing valve actuated by the piston at or near the end of its compression stroke for releasing the pressure into the cylinder to actuate the hammer from a retracted to an impact position.
55. In a power-driven pneumatic tool, in combination, a cylinder housing a working piston and a floating hammer, means for reciprocating the piston, a pressure chamber at one end of the cylinder, a plurality of ports interconnecting the cylinder and the pressure chamber, said ports being so located as to be uncovered by the piston at the end of its compression stroke, a self-closing sleeve valve covering said ports, said valve being opened by the piston near the end of its compression stroke, thereby to release the fluid pressure into the cylinder between the adjacent faces of the piston and hammer to drive the hammer to an impact position.
60. In a power-actuated pneumatic hammer, in combination, a cylinder, a piston and a floating hammer mounted to reciprocate within the cylinder, means for reciprocating the piston to compress a charge of air and exert a retracting influence upon the hammer, a compression chamber closing one end of the cylinder, and a valve mechanically actuated by the piston near the end of its compression stroke for releasing the compressed air from the compression chamber into the cylinder between the piston and hammer to impart a driving force to the hammer at the end of each compression stroke of the piston.
65. In a power-actuated pneumatic hammer, in combination, a cylinder, a piston and a floating hammer mounted to reciprocate within the cylinder, a motor, a power transmission element interposed between the motor and cylinder for transforming the rotary motion of the motor into reciprocatory motion to actuate the piston, said

motor, transmission element and cylinder being joined together to form a unitary structure, a pressure chamber at one end of the cylinder for receiving and holding a charge of air compressed by the piston, said hammer being disposed to trail the piston on its compression stroke, and a valve mechanically operated in response to the piston reaching the end of its compression stroke for releasing the charge of compressed air into the cylinder between the adjacent faces of the piston and hammer to impart a driving force to the floating hammer.

18. A power-driven pneumatic tool comprising, a cylinder provided at one end with a tool chuck and at the opposite end with a pressure chamber having a discharge valve, a piston and a floating hammer within the cylinder, said piston having a retracting influence on the hammer on its compression stroke and functioning to mechan-

ically actuate the discharge valve to actuate the hammer, a casing attached to the cylinder, a crosshead mounted within the casing for reciprocatory movement in line with the piston, said crosshead having longitudinal slots on opposite sides thereof, a piston rod for attaching the piston to the crosshead, a pair of bearing blocks disposed for sliding movement in the crosshead slots, a pair of cranks journaled within the casing on a common axis on opposite sides of the crosshead, said cranks engaging the bearing blocks and adapted when rotated in opposite directions to reciprocate the crosshead and piston, and means including a motor attached to the casing for driving the cranks in opposite directions at equal speeds, thereby to subject the crosshead to balanced driving forces at all times. 5 10 15

ALEXANDER PALMROS.
